SEAR MECHANISM FOR GUNS

Richard C. Coupland, United States Army,
Norfolk, Va.

Application August 2, 1932, Serial No. 627,244

10 Claims. (Cl. 89—27)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a sear mechanism for guns.

In mounting fixed machine guns on aircraft, it is customary to operate the gun by means of a trigger motor synchronized with the propeller 10 of the aircraft and adapted to be placed on either side of the gun. When the gun is mounted in a flexible manner a hand trigger is employed to control the firing mechanism. Where one gun 15 is to be adaptable for all of the methods of operation it is necessary that the slide for releasing the sear be so arranged that it can be actuated from three different directions.

The principal object of this invention is to provide a sear mechanism that will meet the foregoing requirements with a minimum adjustment of parts and that will be operable upon the application of a slight force.

A further object of the invention is to so arrange the sear mechanism that the firing pin 45 will be able to pass through it and strike the buffer plate of the gun.

With the foregoing and other objects in view, the invention resides in the novel arrangement and combination of parts and in the details of 30 construction hereinafter described and claimed, it being understood that changes in the precise embodiment of the invention herein disclosed may be made within the scope of what is claimed without departing from the spirit of the invention.

A practical embodiment of the invention is illustrated in the accompanying drawings, wherein:

Fig. 1 is a longitudinal sectional view through 40 the receiver of a machine gun showing the firing pin held in cocked position by the sear.

Fig. 2 is an enlarged longitudinal sectional view of the rear end of the bolt of Fig. 1.

Fig. 3 is a view similar to Fig. 2 showing the 45 relative position of the parts when the firing pin is in fired position.

Figs. 4 and 5 are views in rear elevation of the bolt corresponding respectively to Figs. 2 and 3.

50 Fig. 6 is a plan view of Fig. 4.

Figs. 7 and 8 are detail views respectively in rear and side elevation of the sear.

Fig. 9 is a plan view of the sear.

55 Figs. 10 and 11 are detail views respectively in plan and rear elevation of the transverse slide.

Fig. 12 shows views in rear and side elevation of the vertically movable slide.

Referring to the drawings by numerals of reference there is shown the receiver frame 5 of a machine gun within which a bolt 6 is reciprocally mounted. Within the bolt is a longitudinally disposed firing pin 7 normally urged in a forward direction by means of a spring 8 housed in the firing pin and seated on a vertical pin 9 passing through the bolt. The firing pin is cocked 60 in a well known manner by the lever 10 when the bolt moves in recoil.

The firing pin is held in cocked position by means of a sear 11 which is mounted for vertical sliding movement in a slot 12 in the rear end of the bolt and is formed with ribs 13 on its opposite sides which fit in grooves 14 in the side walls of the slot. The sear includes a transversely disposed lug 15 movable into and out of a transversely disposed groove 16 formed in the upper surface of the firing pin adjacent its rear end. The rear face 17 of the lug 15 is inclined to coact with a correspondingly inclined face 18 defining the rear wall of the groove 16 in the firing pin.

On the front end of the sear is a bent finger 19 the extremity of which is disposed in the groove 16 of the firing pin when the latter is in the cocked position as shown in Fig. 2. In Fig. 3 where the firing pin is in the firing position the extremity 80 of the finger rests on top of the rear end of the firing pin and serves to hold the sear in the elevated position.

A pair of lugs 20—20 on the sides of the sear, one below each of the ribs 13 and spaced therefrom are provided for a purpose that will appear later. A plunger 21 mounted in the upper portion of the sear and urged outwardly by a spring 22 is seated against a bar 23 rigidly carried by the pin 9. The plunger opposes elevation of the sear, and normally tends to depress it into engagement with the firing pin. The lower portion of the sear is formed with an opening 24 to permit the rear end of the firing pin 7 to strike the buffer plate 25 when the bolt has been arrested by the buffer plate.

The rear end of the bolt is formed with a transversely disposed slot 26 having grooves 27—27 at its inner end. A slide 28, (Figs. 10 and 11) insertable in the grooves 27 from either side 105 of the bolt is disposed in front of the sear. A more or less centrally located aperture 29 in the slide permits the rear portions of the firing pin to move through the slide.

A pair of spaced lugs 30—30 are provided on 110

the rear face of the slide at one side of the aperture 29 and have inclined faces 31-31. These lugs lie in the vertical transverse plane containing the lugs 20-20 on the sear.

- 5 On the other side of the aperture 29 is a housing 32 projecting rearwardly from the slide and integral therewith. A plunger 33 mounted in the housing 32 projects inwardly into engagement with the side of the sear as clearly shown in Fig. 4.

The plunger spring 34 is disposed in the housing 32 and a pin 35 limits extrusion of the plunger under the influence of the spring. The slide is symmetrical about a longitudinal axis 15 so that it may be reversed and inserted from either side of the bolt, depending upon the location of a synchronized trigger motor.

The lower portion of the vertical slot 12 in the bolt includes grooves 36-36 for receiving 20 a vertically movable slide 37. This slide is inserted from above and includes an ear 38 on each side for engaging the floor of the transverse slot 26 and limiting downward movement of the slide. The upper corners of the slide are 25 inclined as at 39 complementary to the inclined faces 31 of the lugs 30. This slide is adapted to be elevated by the hand trigger mechanism of the machine gun.

In Figs. 2 and 4 the lug 15 on the sear is engaged in the groove 16 of the firing pin which is 30 in cocked position and the sear is prevented from being raised by virtue of the engagement of one of its lugs 20 under the lip of the uppermost lug 30 on the slide 28. The slide 28 is 35 maintained in the locking position by means of the spring-pressed plunger 33. When the slide is moved laterally (to the left in Fig. 5) the lug 30 is no longer in the path of movement of the lug 20 on the sear.

40 As soon as the sear is released the firing pin spring 8 moves the firing pin 7 forward, the transverse lug 15 on the sear being cammed out of the groove 16 in the firing pin by virtue of the coaction of the inclined surfaces 17 and 18. 45 Upon elevation of the sear the bent finger 19 is moved out of the groove 16 and the firing pin in moving forward comes to rest with its rear end directly under the finger 19 (Fig. 3). As a consequence the sear is held in the raised position 50 against the action of the plunger 21 which tends to depress it, and it cannot be lowered into the path of the firing pin. In this position of the parts the lug 20 on the elevated sear is in the path of movement of the lug 30 on the slide 28.

55 As the bolt moves in recoil the cocking lever 10 retracts the firing pin against the tension of the firing pin spring. As soon as the finger 19 is clear of the rear end of the firing pin the sear is depressed by its spring into the groove 16.

60 This depression of the sear moves the lug 20 below the lug 30 on the slide 28 and the slide under the influence of its spring immediately moves laterally of the bolt and positions the lug 30 above the lug 20 thereby locking the sear and firing pin in cocked position.

The slide 28 is actuated directly from the side of the bolt or it is actuated indirectly through the vertical slide 37.

I claim:

70 1. In a gun, a reciprocal breech bolt, a firing pin having a groove adjacent its rear end and movable relative to the bolt, a cocking lever for the firing pin, a vertically movable sear carried by the bolt and adapted to be elevated by the firing pin on forward movement thereof, a spring 75

normally tending to depress the sear into engagement with the firing pin to hold the same in cocked position, means on the sear disposed in the groove of the firing pin when cocked and engageable with the firing pin when fired whereby the sear is held in the elevated position, a lug on each side of the sear, a transversely movable slide reversibly mounted in the bolt in front of the sear and having an aperture through which the firing pin is movable, a pair of spaced lugs 80 on said slide in the plane of the lugs on the sear, one of the lugs on the sear engageable under one of the lugs on the slide when the sear is depressed, a plunger on the slide engageable with the sear and normally holding the slide in sear-locking position, and a vertically movable slide 85 in the bolt operable to move the transverse slide out of sear-locking position.

2. In a gun, a reciprocal breech bolt, a firing pin having a groove adjacent its rear end and movable relative to the bolt, a cocking lever for the firing pin, a vertically movable sear carried by the bolt and adapted to be elevated by the firing pin on forward movement thereof, a spring 90 normally tending to depress the sear into engagement with the firing pin to hold the same in cocked position, means on the sear disposed in the groove of the firing pin when cocked and engageable with the firing pin when fired whereby the sear is held in the elevated position, a lug on each side 95 of the sear, a transversely movable slide reversibly mounted in the bolt in front of the sear and having an aperture through which the firing pin is movable, a pair of spaced lugs on said slide in the plane of the lugs on the sear, one of the lugs on the sear engageable under one of the lugs on the slide when the sear is depressed, and a plunger on the slide engageable with the sear and normally holding the slide in sear-locking position.

3. In a gun, a reciprocal breech bolt, a firing pin having a groove adjacent its rear end and movable relative to the bolt, a cocking lever for the firing pin, a vertically movable sear carried by the bolt and adapted to be elevated by the firing pin 100 on forward movement thereof, a spring normally tending to depress the sear into engagement with the firing pin to hold the same in cocked position, means on the sear disposed in the groove of the firing pin when cocked and engageable with the firing pin when fired whereby the sear is held in the elevated position, a lug on each side 105 of the sear, a transversely movable slide reversibly mounted in the bolt in front of the sear and having an aperture through which the firing pin is movable, a pair of spaced lugs on said slide in the plane of the lugs on the sear, one of the lugs on the sear engageable under one of the lugs on the slide when the sear is depressed, and a plunger on the slide engageable with the sear and normally holding the slide in sear-locking position.

4. In a gun, a reciprocal breech bolt, a firing pin movable relative to the bolt, means for cocking the firing pin, a vertically movable sear carried by the bolt and adapted to be elevated by the firing pin on forward movement thereof, a spring 110 normally tending to depress the sear into engagement with the firing pin, means on the sear engageable by the firing pin whereby the sear is held in the elevated position, a transversely movable slide reversibly mounted in the bolt in front of the sear and having an aperture through which the firing pin is movable, a lug on said slide in the plane of the lug on the sear, the lug on the sear engageable under the lug on the slide when the sear is depressed, and a plunger on the slide engageable with the sear and normally holding the slide in sear-locking position.

5. In a gun, a reciprocal breech bolt, a firing 115

pin movable relative to the bolt, means for cocking the firing pin, a vertically movable sear carried by the bolt and adapted to be elevated by the firing pin on forward movement thereof, a spring normally tending to depress the sear into engagement with the firing pin, means on the sear engageable by the firing pin whereby the sear is held in the elevated position, a transversely movable slide reversibly mounted in the bolt in front of the sear and having an aperture through which the firing pin is movable, and means for normally moving the slide into position to engage the sear.	the firing pin, a vertically movable sear carried by the bolt and adapted to be elevated by the firing pin on forward movement thereof, means normally tending to depress the sear into engagement with the firing pin, a lug on each side of the sear, a transversely movable slide reversibly mounted in the bolt, a pair of spaced lugs on the slide, one of the lugs on the sear engageable under one of the lugs on the slide when the sear is depressed, a plunger on the slide engageable with the sear and normally holding the slide in sear-locking position, and a vertically movable slide in the bolt engageable with one of the lugs on the slide to move the slide out of sear-locking position.	80
6. In a gun, a reciprocal breech bolt, a firing pin movable relative to the bolt, means for cocking the firing pin, a vertically movable sear carried by the bolt and adapted to be elevated by the firing pin on forward movement thereof, a spring normally tending to depress the sear into engagement with the firing pin, means on the sear engageable by the firing pin whereby the sear is held in the elevated position, a transversely movable slide mounted in the bolt in front of the sear and having an aperture through which the firing pin is movable, and means for normally moving the slide into position to engage the sear.	9. In a gun, a reciprocal breech bolt, a firing pin movable relative to the bolt, means for cocking the firing pin, a vertically movable sear carried by the bolt and adapted to be elevated by the firing pin on forward movement thereof, a spring normally tending to depress the sear into engagement with the firing pin, a lug on each side of the sear, a transversely movable slide reversibly mounted in the bolt, a pair of spaced lugs on the slide, one of the lugs on the sear engageable under one of the lugs on the slide when the sear is depressed, and a plunger on the slide engageable with the sear and normally holding the slide in sear-locking position.	90
7. In a gun, a reciprocal breech bolt, a firing pin movable relative to the bolt, means for cocking the firing pin, a vertically movable sear carried by the bolt and adapted to be elevated by the firing pin on forward movement thereof, means for normally depressing the sear into engagement with the firing pin, a finger on the sear engageable by the firing pin when the firing pin is in forward position whereby the sear is held in the elevated position, and a slide working between the sear and the finger for locking the sear.	10. In a gun, a reciprocal bolt, a firing pin movable relative to the bolt, means for cocking the firing pin, a sear engageable with the firing pin to hold it in cocked position, a sear-lock reversibly mounted in the bolt whereby it may be operated in reversed directions to release the sear, and a slide carried by the bolt operable to move the sear-lock in both arrangements of its mounting.	100
8. In a gun, a reciprocal breech bolt, a firing pin movable relative to the bolt, means for cocking	RICHARD C. COUPLAND.	115
